Primary Examiner — Vy N Koenig

Assistant Examiner — Kimberly Barnes

(74) Attorney, Agent, or Firm — Fish & Richardson P.C.

(57) **CLAIM**

The ornamental design for a slab of particulate mineral mixture, as shown and described.

DESCRIPTION

The file of this patent contains at least one drawing/photograph executed in color. Copies of this patent with color drawing(s)/photograph(s) will be provided by the Office upon request.

The sole FIGURE is a top plan view of a slab of particulate mineral mixture, showing our new design. The depicted surface of the slab is flat.

**1 Claim, 1 Drawing Sheet
(1 of 1 Drawing Sheet(s) Filed in Color)**
